UNITED STATES PATENT OFFICE.

HERBERT W. EASTMAN, OF CEDAR RAPIDS, IOWA.

CARBON REMOVER.

No Drawing.

Application filed May 11, 1920. Serial No. 380,497.

To all whom it may concern:

Be it known that I, HERBERT W. EASTMAN, a citizen of the United States, residing at Cedar Rapids, in the county of Linn 5 and State of Iowa, have invented certain new and useful Improvements in Carbon Removers, of which the following is a specification.

This invention relates to a compound for 10 removing carbon deposit from the cylinders of internal combustion engines, spark plugs, valves and the like, the object being to provide a compound which will free the deposit and one which when placed in the cylinder 15 of an internal combustion engine will loosen the carbon deposit and place it in condition to be discharged or consumed in the operation of the engine.

The carbon compound is formed of alcohol, acetone, sulphuric ether, stronger ammonia water, and chloroform, which are 20 thoroughly mixed and let stand for forty-eight hours to allow several chemical reactions to take place between the ingredients 25 of the composition. One gallon of alcohol is added to the ether before mixing all of the other ingredients. The composition is then filtered and placed in bottles and is ready to be used by placing a small portion 30 of the same in the cylinder of an internal combustion engine for removing the carbon therefrom, or a valve or spark plug can be immersed in the composition which will

loosen the carbon deposit so that the same can be readily wiped from the spark plug 35 or valve.

The carbon removing composition consists of the following ingredients, preferably in the proportions stated, although these portions may be varied more or less without materially injuring the properties of the product. 40

Alcohol	-----	80 gallons
Acetone	-----	15 gallons
Sulphuric ether	-----	4 gallons
Stronger ammonia water	-----	100 gallons
Chloroform	-----	4 gallons

In mixing the ingredients they are preferably placed in the container and mixed together in the order named, and before the ether is placed in a gallon of alcohol is mixed with the same. The solution of ammonia used is preferably 26 per cent. 50

What I claim is:—

A carbon removing composition consisting of 80 gallons of alcohol, 15 gallons of acetone, 4 gallons of sulphuric ether, 100 gallons of stronger ammonia water, and 4 gallons of chloroform. 60

In testimony whereof I hereunto affix my signature in the presence of two witnesses.

HERBERT W. EASTMAN.
